UNITED STATES PATENT OFFICE.

CHARLES L. KLINE, OF NEW YORK, N. Y.

CAR-HEATING SYSTEM.

SPECIFICATION forming part of Letters Patent No. 417,391, dated December 17, 1889.

Application filed November 14, 1888. Serial No. 290,839. (No model.)

To all whom it may concern:

Be it known that I, CHARLES L. KLINE, a citizen of the United States, residing at New York, in the county of New York and State 5 of New York, have invented certain new and useful Improvements in Car-Heating Systems; and I do hereby declare the following to be a full, clear, and exact description of the invention, such as will enable others skilled in the 10 art to which it appertains to make and use the same.

The object of my invention is broadly to provide means for heating and ventilating railway-cars. In carrying out this object I 15 employ pipes which run through the cars to be heated, and are connected with suitable valves and radiators, the pipes being passed through the fire-box of the locomotive and being joined with blowers which pump the 20 heated air through them. Incidentally, therefore, my invention is concerned with providing means for protecting the pipes in the fire-box, and with various other details, which will be fully explained hereinafter.

25 My invention is illustrated in the accompanying drawings, in which—

Figure 1 is a plan of my heating system with skeletons of cars and locomotives. Fig. 2 is an elevation and part section of a locomotive with my devices attached. Figs. 3, 4, 30 5, and 6 show details.

Referring to the drawings by letter, A and B are a pair of blowers on the locomotive, connected, respectively, with the pipes C and 35 D, which run back through the train, suitable couplings being provided between the cars. In the present invention the pipes are left open to the air at the rear of the train. Before leaving the locomotive they both 40 pass through the fire-box E, being suspended loosely therein by hangers F F, so as to admit of movement of said pipes laterally through said hangers to prevent binding or rupture of these parts while expanding or contracting. It will be observed that the 45 pipes are coiled in traversing the fire-box, so as to present as much surface as possible to the heat. In order to minimize the effect of the heat or the flames to which they are

likely to be subjected, the pipes are covered 50 with what is known as a "crucible coating," or any other composition suitable for the purpose. By these means the flaking and burning away of the pipes are prevented.

Figs. 3, 4, and 5 show the details of the 55 hangers. They consist of pipes of circular form suspended from the top plate e of the fire-box by hollow screws f f. The upper hangers are connected with the lower by similar means. The screws being hollow and 60 the hangers being pipes, they will all become filled with water or steam from the boiler, and so be protected from the excessive heat of the fire-box.

In traversing the cars the pipes pass 65 through radiators G G. Joined to them at short intervals, preferably under each seat, are valves H H, (shown in detail in Fig. 6,) leading to perforated globes h, through which the heated air may be caused to flow freely 70 when it is desired to heat a car rapidly, as when a cold car is taken on at a station.

The blowers are joined by belts or gearing to one of the axles of the forward truck of the locomotive. They draw their supply 75 directly from the open air, and in connection with the valves H H may be employed to ventilate as well as heat the cars. In the drawings I show a set of gear-wheels or pulleys P P' P'', for joining the blower-shaft to 80 the axle. The last-named pulley is beveled to allow for the turning of the truck-axle in going around curves. The middle gear-wheel is supported on a frame R, which may be made wide enough to prevent interference 85 from snow or other obstructions.

At J, I show an injector connected with one of the pipes and preferably with the dome of the boiler. There may be injectors connected with both pipes. The object is to 90 supply a current when the locomotive is stationary.

Having now described my invention, I claim—

1. In a car-heating system, a pipe running 95 through the fire-box of a locomotive, the said pipe being loosely supported from the top plate of the fire-box by hangers in the form

of pipes and hollow screws, as and for the purpose set forth.

2. In a car-heating system, a pipe passing through the fire-box of a locomotive, the said pipe being covered with a crucible coating, and being loosely supported in hangers in the form of pipes, which hangers are connected to the top plate of the fire-box by hollow screws, as and for purpose set forth.

In testimony whereof I have affixed my signature in presence of two witnesses.

CHARLES L. KLINE.
